United States Patent Office.

CHARLES J. SHUTTLEWORTH, OF SPRINGVILLE, NEW YORK.

Letters Patent No. 92,664, dated July 13, 1869.

IMPROVED HORSE-POWER.

The Schedule referred to in these Letters Patent and making part of the same.

To all whom it may concern:

Be it known that I, CHARLES J. SHUTTLEWORTH, of Springville, in the county of Erie, and State of New York, have invented a certain new and improved Horse-Power; and I do hereby declare that the following is a full and exact description, reference being had to the accompanying drawings, making part of this specification.

My invention consists in the general arrangement of a loose bevel-wheel and pinion on the gear-frame axis, with the other gearing and gear-frame.

In the drawings—

Figure I is a central vertical section of my improved horse-power, in line x x , Fig. II.

Figure II is a plan of the same.

Like letters of reference designate like parts in each of the figures.

A is the bevel-gear rim, and A^1 , the friction-track, cast together with the same pitch-line, and supported on suitable standards A^2 A^3 , connecting with base-pieces A^4 , which supporting-frame may be cast with the ring A A^1 , if desired.

B is a cross-piece, resting upon and bolted to the base-pieces A^4 .

This casting supports a central stationary shaft, C, which forms the axis of the gear-frame D, and of the combined bevel-wheel and pinion E E' .

The frame D is a plate casting, constructed with a central cross-piece, D', having a hub, d, at the centre, upwardly through which projects the axis C, provided with a washer and pin, e and e', at its upper end, to prevent the rising of the frame.

F F' are two bevel-pinions, meshing with the gear-rim A, and

F' F'' , two friction-wheels traversing the track A^1 .

These pinions and wheels are arranged in pairs, one of each being keyed together on the same horizontal shaft G, and formed with the same pitch-line, so as to revolve together with the same velocity, without any slipping of the friction-wheels on the track.

The shafts G have their bearings in suitable boxes g, on top of the frame D, and have mounted on their

inner ends bevel-gear wheels H H' . These bevel-wheels mesh with the bevel-pinion E between them.

The pinion E and wheel H are secured or cast together, and revolve loosely on the shaft C.

The wheel H meshes with a bevel-pinion, I, mounted on a horizontal shaft, J, which has its bearings in the cross-piece B, and to which are jointed the tumbling-rods K.

L L are two sweeps, to which the horses are attached for operating the power.

They may be secured to the gear-frame by means of a bolt, L, and by casting with the frame upwardly-projecting flanges m m, to receive the end of each lever, and with a similar flange or shoulder, m', which acts as a fulcrum, against which the lever presses. A greater number of sweeps may be employed, if desired.

N N are two friction guide-wheels, traversing the inner edge or circumference of the ring A A^1 , and attached to projecting ears of the gear-frame at opposite points, and in such a position as to best oppose the strain that would otherwise come on the axis C in operating the machine.

The construction and arrangement of the friction-rollers and the gearing, as before described, enable the gear-frame to be supported by said friction-rollers, whereby the excessive friction which would result from the gearing meshing too deeply, if the frame were not thus supported, is prevented.

The weight of the gear-frame pressing on the friction-wheels, causes them to act efficiently as traction-wheels, in conjunction with the pinions F, in driving the other gearing.

What I claim as my invention, and desire to secure by Letters Patent, is—

The general arrangement of the bevel-gear wheels H H' , wheel and pinion E E' , and pinion I, with the gear-frame, axis C, and said driving-gear, substantially as set forth.

Witnesses: C. J. SHUTTLEWORTH.

C. C. SEVERANCE,
A. W. STANBRO.
